UNITED STATES PATENT OFFICE.

CAMPBELL E. ARNOLD, OF TAMPA, FLORIDA.

LOCOMOTIVE.

1,235,412.

Specification of Letters Patent. Patented July 31, 1917.

Application filed May 31, 1916. Serial No. 100,919.

To all whom it may concern:

Be it known that I, CAMPBELL E. ARNOLD, a citizen of the United States, residing at Tampa, in the county of Hillsborough and 5 State of Florida, have invented certain new and useful Improvements in Locomotives, of which the following is a specification.

This invention relates to locomotives, particularly to that type provided with an 10 air compressor for supplying supplementary pressure, and has for its object the provision of a novel form of superheater whereby the steam alone, or steam and compressed air, or compressed air alone may be addi- 15 tionally heated to secure the maximum pressure, and whereby all the energy of the heat within the locomotive may be utilized.

Other objects and advantages such as the enlarged space around my improved super- 20 heater, novel means of transmitting the air and steam, simplicity, durability, cheapness in manufacture, and the general improvement of the art will be more fully brought out in the following specification and illus- 25 trated in the accompanying drawings in which:

Figure 1 is a side view of a complete locomotive embodying my invention,

Figs. 2 and 2^a a side view of my improved 30 locomotive on a larger scale and having parts of the exterior removed to show the relative positions of the inner parts,

Figs. 3 and 3^a an enlarged sectional view 35 of the locomotive proper, and

Figs. 4, 5, 6, 7 and 8 are detail views of the throttle valve.

Referring more particularly to the drawings in which like reference numerals designate the like parts in the several views there- 40 of, the numeral 1 designates a locomotive which is of the usual construction comprising a cab 2, a fire box 3, a boiler 4, and boiler flues 5.

My improved super-heater 6 comprising a 45 reservoir 7 and a funnel shaped flue portion 8 is secured to the boiler of a locomotive in place of the usual smoke box and super- heater. An exhaust chamber 9 is also formed within the reservoir 7 and commu- 50 nicates with the flue portion 8. An exhaust nozzle 10 is formed within the exhaust chamber 9 and communicates with the cyl- inders of the locomotive. The exhaust chamber 9 has a manhole formed therein 55 closed by a cover 11 having ground air tight joints 12. Steam is received from the boiler

into the super-heater when necessary through a pipe 13 entering at the bottom of the super-heater reservoir, and compressed air is received through the pipe 14 60 from a compressor 15 of any well-known or preferred type, the pipe 14 entering adjacent the front portion of the reservoir 7.

The compressed air or steam enters the cylinders through a throttle-valve 16 to be 65 described and then through the Y head 17 and through the pipes 18 on each side of the superheater to the cylinders. Access is had to the super-heater or any of the parts within it through a door 20 having air tight 70 joints 21.

The throttle-valve 16 comprises a casing or cylinder 22 a rotary valve 23 having a groove 24 therein to connect with the port 25 in the Y head 17 to permit the passage 75 of the steam or air to the cylinders of a locomotive. The throttle valve 16 is operated by a bell crank 26 keyed to the rotary valve 23. The bell crank 26 is connected with the engine cab by a rod 27 having an 80 operating handle 28.

The tender 29 of the engine when constructed according to my invention becomes an integral part thereof although it is de- 85 tachably and flexibly connected as at 30.

The tender 29 has a fuel portion 31 and carries the air compressor 15, which may conveniently be operated by a steam turbine 32 which receives steam from the engine boiler through a pipe 33. The compressed 90 air is of course stored in a suitable tank 34 with which the pipe 14 communicates through a reducing valve 35.

The pipes 33 and 14 have the usual flexible joints between the locomotive and tender to 95 allow for movement in any direction caused by travel.

The operation of the device is as follows: The steam from the boiler is admitted through the pipe 13 to the superheater 6, 100 where it is additionally heated and expanded, and whence it passes through the throttle valve 16 and into the engine cyl- inders through the pipes 18. The com- pressed air passes from the tank 34 through 105 the pipe 14 into the superheater and even- tually into the engine cylinders in the same manner as the steam. The steam alone, the compressed air alone, or both steam and air mixed may be supplied optionally to the 110 superheater as various emergencies may render necessary. The exhaust from the engine

cylinders passes through the nozzle 10 into the chamber 9 and out into the atmosphere, producing the requisite draft on the fire in the fire-box of the engine.

5. From the foregoing description and a study of the drawings it will be apparent that I have thus provided a novel and efficient form of device whereby steam, compressed air, or steam and air may be additionally heated and expanded for supplying the maximum degree of pressure to the cylinders of a locomotive.

10 It will be readily understood that I may make such changes in the form, construction and arrangement of parts as will not depart from the spirit of the invention and such as will be within the scope of the claims.

15 Having thus described my invention what I claim is:

20 1. In a compressed air locomotive, a superheater comprising a funnel shaped heat unit through which the products of combustion pass from said locomotive, a chamber surrounding said unit, and means for allowing the passage of compressed air and steam into said chamber and other means for allowing the passage of said air and steam into the cylinders of said locomotive.

25 2. In a locomotive, a superheater comprising a funnel shaped heat unit through which the products of combustion pass, a chamber surrounding said unit, and means for allowing the passage of compressed air and steam into said chamber, other means for allowing the passage of said air and steam into the cylinders of said locomotive, and means for controlling said last named passage.

30 3. In a locomotive, a superheater comprising a funnel shaped heat unit, a chamber surrounding said unit, and means for

allowing the passage of compressed air and steam into said chamber, other means for allowing the passage of said air and steam into the cylinders of said locomotive, and 45 means for controlling said last named passage, said means comprising a throttle valve located at the rear of said superheater and adapted to be operated from the locomotive cab.

50 4. In combination with a combined steam and compressed air locomotive, a superheater comprising a flue extending over the ends of and coaxially with the boiler tubes, an outlet stack communicating with said flue and with the atmosphere, a heating chamber surrounding said flue and said stack and having selective valved communication with a steam supply and a compressed air supply, and valve controlled outlet means 60 communicating with said chamber and with the engine cylinders.

5. In combination with a combined steam and compressed air locomotive, a superheater comprising a flue extending over the 65 ends of and coaxially with the boiler tubes, an outlet stack communicating with said flue and with the atmosphere, a heating chamber surrounding said flue and said stack and having selective valved communication with a steam supply and a compressed air supply, valve controlled outlet means communicating with said chamber and with the engine cylinders, and a draft producing discharge nozzle within said outlet stack communicating with the exhaust of the engine cylinders and terminating adjacent the point of entry of said flue into said stack.

75 6. In testimony whereof I hereto affix my 75 signature.

CAMPBELL E. ARNOLD.
